SHEET FEEDING MECHANISM

Ernest G. Rider, Philadelphia, Pa.

Application December 17, 1941, Serial No. 423,273

11 Claims. (Cl. 271—43)

The present invention relates to a paper feeding mechanism and more particularly to means for removing one sheet at a time from a stack and delivering such sheets successively to a predetermined location.

In devices as heretofore designed to separate and remove sheets in succession from a stack of sheets it has been proposed to employ friction rollers for propelling the top sheet away from the stack; means utilizing liquid glue or adhesive in conjunction with a lifting mechanism; sticky picker cylinders controlled by cumbersome counter-weight means and, most frequently, suction devices. All such are open to objections and have many disadvantages from a practical standpoint. For example liquid adhesive is subject to temperature changes and the desired minute quantity required is practically impossible to control. Too much adhesive smears and damages the sheets, too little is ineffective, and even when temporarily adjusted will pick off part of the sheet surface. Friction rollers arranged to propel a sheet more often than otherwise transmit pressure to the next following sheet or sheets and instead of one sheet being removed two or more are simultaneously shifted to cause clogging of the feeding rolls. Suction devices frequently pick up a plurality of sheets simultaneously and require a great and continuing consumption of power.

Some of the objects of the present invention are to provide a mechanism for removing sheets from a stack without any of the previous disadvantages developing during operation; to provide a mechanism for successively removing sheets from a stack and delivering each sheet to feeding rolls or other apparatus, such mechanism operating efficiently and continuously without soiling, crumpling or otherwise impairing the sheets for further use; to provide a sheet handling mechanism including an adhesive strip capable of adjustment while in use for varying the sheet pick-up mechanism wherein replaceable rolls of strip adhesive can be used; to provide a sheet pick-up mechanism which unfailingly engages only a single sheet; to provide a pick-up mechanism which requires no particular power requirements other than those normally attaching to the device with which the pick-up is associated; to provide a sheet feeding mechanism of extreme economy of operation while of enhanced efficiency; to provide a positive effective pick-up mechanism utilizing materials available universally at low cost for its effective engagement of the respective sheets; and to provide other improvements as will hereinafter appear.

In the accompanying drawings Fig. 1 represents a side elevation of a sheet pick-up mechanism embodying one form of the present invention; Fig. 2 represents a fragmentary side eleva-

tion showing the parts in sheet delivery position; Fig. 3 represents an end elevation of a portion of the machine to which the mechanism of the invention is attached; Fig. 4 represents an enlarged detail of the pick-up in contact with a sheet; Fig. 5 represents a side elevation on a larger scale of a modified form of the invention including a mechanism for step-by-step control; Fig. 6 represents a perspective detail of a sheet separating device; and Fig. 7 represents another modification of sheet separating means.

Referring to the drawings one form of the present invention is shown assembled as a part of a standard sheet gluing machine, such, for example as a Stokes and Smith machine (see U. S. Patent No. 1,772,344) wherein a table 10 supports a stack of sheets 11 which are to be removed one at a time for applying glue or other coating to one side thereof. The table 10 is arranged for vertical travel at definite intervals through suitable intermittent motion applied to a plunger 12 upon which the table 10 is mounted. Conveniently located adjacent the delivery point of the respective sheets are two coating but relatively separable feed rolls 13 and 14 for directing each sheet to the stripper plates 15 for guiding the sheets successively under a guide roll 16 against the face of the glue applying roll 17. The glue or other material is contained in a receptacle 18 and a roll 20 rotates in the liquid and also in contact with the roll 17, which latter carries the deposited glue to the sheet. The sheets after coating are directed by a guide scraper 21 to a conveyor 22 which generally leads to a machine for applying the glued sheets to containers. The roll 13 is provided with a circumferential groove 23 which is juxtaposed with respect to a like groove 24 in the roll 14, to thus provide clearance for a movable part presently to be described.

For the purpose of removing the sheets 11 from the stack one at a time, a strip 25 of material, having adhesive on one side, is employed, the same being stretched about a blunt-ended substantially V-shaped pick-up finger 26 which is here shown as an extended part of a carrier plate 27. In the preferred form of the invention the strip 25 is wound glue side in about a hub 28 having, as an integral part, a brake drum 30 provided with a V-shaped periphery. This hub 28 is mounted upon a pin 31 attached to and projecting laterally from the carrier plate 27 adjacent to the base of the pick-up finger 26. Also attached to the side of the plate 27, is a cylinder 32 having its axis alined with the brake drum 30 and housing a spring pressed plunger 33, the projecting end of which conforms to the V-shaped periphery of the drum 30. Under the action of its adjusted spring the plunger 33 maintains just sufficient tension upon the strip 25 to ensure proper operation.

In order to spool up the used portion of the strip 25, a rewind roller 34 is journalled on a pin 35 projecting from the face of the plate 27, and has a ratchet wheel 36 attached thereto for step-by-step operation. An operating pawl 37 is pivoted upon a rock arm 38 which pivots on the pin 35 and has a spring 40 to retract the arm 38 and hold it against a stop 41. A back lash pawl 42 is pivoted to the plate 27 in position to seat in the teeth of the ratchet wheel 36 as will be understood. The rock arm 38 has an extension forming a tapered detent 43 which at certain times is engaged by an abutment lug 44 carried by a pivoted bell crank 45.

As a means for bringing a sheet from the stack 11 into position for engagement by the feed rolls 13 and 14, the plate 27 is attached to a rod 46 by a set screw 47, or other fastening means. The ends of the rod 46 terminate respectively in rock links 48 and 49 respectively mounted on pivots 50 for operation by links 51 from bell cranks 52. Each of these bell cranks carries a cam roller 53 riding in the groove 54 of a side face cam 55. The action of this cam 55 is to swing the plate 27 from contact position with the top sheet of the stack to a position where the feed rolls can engage the end of the sheet and deliver it to the stripper plate and gluing roll.

For moving the feed rolls 13 out of the path of a sheet as the latter is being carried by the pick-up device, the ends of the rolls 13 are journalled respectively in two legs 56 of each of two bell cranks, which are pivoted at 57, and the other legs 56 of which terminate respectively in rollers 60 which ride respectively against the edges of two plate cams 61. The cam surfaces are so laid out as to cause the roll 13 to swing away from the roll 14 as the pick-up finger 26 rises so that the end of the sheet can pass the roll 13, and as this takes place the roll 13 swings back to feeding position as it engages the lower side of the sheet and brings the sheet against the roll 14 to be fed forward and away from the pick-up device. The cam rollers 60 are maintained in contact with the face of the plate cams 61 by means of follower rods 62 attached to the respective legs 56 and each guided by a fixed boss 63, which latter serve to maintain coil springs 64 under compression. These springs 64 encircle the respective rods 62 and bear respectively against yokes 65 which have pivotal connection with the bell crank legs 56. As shown the side face cams 55 are formed in the plate cams 61 for simplified construction.

In order to prevent one or more sheets adhering to the sheet being removed by the pick-up device, a separating element 66 is provided, this, in the present instance, being in the form of a saw-tooth strip fixedly mounted to project into the path of the upwardly moving edge of a picked up sheet. Thus the edge of the sheet, which is being lifted by the pick-up finger 26, brushes across the face of the element 66 but the edge of any following sheet (one improperly adhering to the lifted sheet) is engaged by the element 66 and caused to drop back upon the stack of sheets.

For shifting the abutment lug 44 to a position to cause the rewind roller 34 to wind off a portion of the used adhesive tape and replace it by a fresh portion, the bell crank 45 is arranged to be operated by a link 67 connected to an arm 68 of a rock-plate 70 which is pivoted on a shaft 71 for movement relative thereto. The rock-plate 70 is normally held by a stop 72, in such a position as will maintain the bell crank 45 in its inoper-

ative position. Thus the stop 72, which is formed as a projecting part of the rock-plate 70, rests against the end of a stud 73, under the influence of a tension spring 74 stretched between a fixed point and the arm 68. The stud 73 is arranged to be withdrawn from its stop holding position at certain selected intervals, and, in the present instance, a lever 75 is located with one end beneath the head of the stud 73 and its other end 10 extending into the path of a trip tappet 76. The lever 75 is pivoted at 77 intermediate its ends. The stud 73 is mounted to be slidably guided in a vertically disposed sleeve 78, while a pin 80 limits the downward movement of the stud 73. The trip tappet 76 is keyed to the rock-shaft 50 and therefore follows the movement of the pick-up device so that the latter becomes a control for determining the time of operation of the rewind roller 34. Thus as each sheet is removed from the stack, the 20 pick-up device and the trip tappet 76 move down by the thickness of one sheet, and when, for example, ten sheets have been removed the trip tappet 76 strikes the lever 75 to raise the stud 73 out of the path of the stop 72, and consequently 25 the spring 74 rocks the plate 70 (clockwise as shown) to pull the link 67 down and throw the lug 44 into the path of the detent 43. Now as the pick-up plate swings upward the detent will be rocked forward by contact with the lug 44 30 and thereby cause the rewind ratchet to be turned preferably one tooth.

For the purpose of raising the table 10 after a selected number of sheets have been removed, the plunger 12 is provided with a rack 81 in mesh 35 with a pinion 82 keyed to the shaft 71. Also keyed to the shaft 71 is a ratchet wheel 83 arranged to receive a step-by-step movement through a pawl 84 pivoted to the arm 68. A back-lash pawl 85 is provided to also engage the wheel 83 for the usual purpose. The operating movement of the pawl 84 is brought about by a power driven connecting rod 86 which has a lost motion connection with a pin 87 fixed to the plate 70. A cam or other suitable intermittent mechanism can be employed to actuate the rod 86 in a well known manner. Thus when the stud 73 releases the stop 72 the plate 70 rocks to shift the control bell crank 45 and also brings the pawl 84 back upon the ratchet wheel 83 in position to transmit motion to the shaft 71 so that the pinion 82 elevates the table 10 the necessary distance to bring a top sheet to the normal level of the pick-up device.

From the foregoing it will be seen that the pick-up device is intimately associated with the table elevating mechanism and in addition to lifting sheets serves to control both the feeding of the adhesive strip and the table at times determined by the selected number of removed sheets.

In the form of the invention shown in Fig. 7, 60 a means is provided to move a separating member 88 into and out of operative relation to the stack of sheets. This may be used in place of the one or more separating members 66, or in conjunction therewith, or may be used alone. 65 Preferably this member 88 is located to coact with the sheet edges near the center thereof because here it functions to space and to slightly elevate the sheets in spaced relation while the members 66 near the sides of the sheet stack function to restrain the sheets and thus to enhance the separation and thus ensure an accurate pick-up of the topmost sheet only. As shown the member 88 is in the form of a saw blade but the invention 70 is not limited in this respect as other forms of

roughened edges or surfaces may be employed. The member 88 is pivoted at 90 to a holder 91 which, illustratively only, is fixed to the shaft forming the connection between the links 51 and the bell cranks 52, so as to be moved in synchronism with the movement of the pick-up finger 26 by the same actuating linkage. Obviously any other actuating mechanism may be employed as desired. In the form illustrated as the links 51 move, to the right as shown on the drawings, the plate 27 is rocked in the direction to lower the pick-up finger 26 into contact with the top sheet of a stack of sheets. The separating member 88 moves in timed synchronism with the movement of the links 51 and, in the preferred form at least, is so timed as to meet the edges of the sheets just prior to the attainment of the contact position of the pick-up finger 26. Since the member 88 is pivoted the contact of its edge with the sheet causes it to swing slightly about its pivot, which action is translated into an upward movement approximately parallel to the plane of the stack edges. As the initial contact of the member 88 with the sheets exerts a pressure against the edges, the foregoing upward movement acts as an effective means to separate the several top sheets one from another. The result is that the pick-up finger 26 can lift the top sheet entirely free from the following sheets.

Obviously this separation is enhanced when a stationary brush or other means is used at one point at the sheet edge while the movable member 88 is applied to the sheet edges at a different point on such edges.

Having thus described my invention, I claim:

1. A sheet feeding mechanism comprising a strip of material having a surface coated with adhesive, means to mount said strip in stretched condition, said means being contoured to provide a line contact between said strip and a sheet of material, and means to shift said mounting means to deliver a sheet picked up by said strip to a selected location.

2. A sheet feeding mechanism comprising a strip of material having a surface coated with adhesive, means to mount said strip in stretched condition, said means being contoured to provide a line contact between said strip and a sheet of material, a device for changing the contact line of said strip, and means to shift said mounting means to deliver a sheet picked up by said strip to a selected location.

3. A sheet feeding mechanism comprising a support, a strip of material having a surface coated with adhesive and wound into a spool, means rotatably mounting said spool on said support, a pick-up finger holding a length of said strip in stretched condition for contact with a sheet, means to feed said strip from said spool to vary the relation with said pick-up finger, and means to shift said pick-up finger to deliver a sheet held by said strip to a selected location.

4. A sheet feeding mechanism comprising a support, a strip of material having a surface coated with adhesive and wound into a spool, means rotatably mounting said spool on said support, a pick-up finger holding a length of said strip in stretched condition for contact with a sheet, a tension device for maintaining said strip in stretched condition, means to feed said strip from

said spool to vary the relation with said pick-up finger, and means to shift said pick-up finger to deliver a sheet held by said strip to a selected location.

5. A sheet feeding mechanism comprising a support, a strip of material having a surface coated with adhesive and wound into a spool, means rotatably mounting said spool on said support, a pick-up finger holding a length of said strip in stretched condition for contact with a sheet, automatically operated step-by-step means to feed said strip from said spool to vary the relation with said pick-up finger, and means to shift said pick-up finger to deliver a sheet held by said strip to a selected location.

6. A sheet feeding mechanism comprising a support, a strip of material having a surface coated with adhesive and wound into a spool, means rotatably mounting said spool on said support, a pick-up finger coating with said strip to cause a portion of said strip to contact a sheet to be removed from a stack of sheets, said finger being carried by said support, means to oscillate said support to vary the position of said strip relative to said finger, whereby fresh adhesive surfaces are brought into use at intervals.

7. A sheet feeding mechanism comprising a movable pick-up finger for transferring a sheet of material from a sheet stack to another location, means to stretch a strip of adhesive material about said finger for pick-up contact with said sheet, and means to vary the position of said strip relative to said finger whereby different sheets are engaged by different strip areas.

8. A sheet feeding mechanism comprising a movable pick-up finger for transferring a sheet of material from a sheet stack to another location, means to stretch a strip of adhesive material about said finger for pick-up contact with said sheet, and step-by-step means for feeding said strip about said finger whereby different sheets are engaged by different strip areas.

9. A sheet feeding mechanism comprising a support for a stack of sheets, a member movable relative to said support, a strip of adhesive material carried by said member in position to cause an area of said strip to contact the top sheet of a stack on said support, and means to replace a used contact area of said strip with an unused contact area.

10. A sheet feeding mechanism comprising a support for a stack of sheets to be separated, a sheet separating device having a plurality of substantially linearly disposed teeth, and means for moving said device toward the side of said stack and angularly upwardly along the face of said stack to separate the edge portion of one or more sheets from the stack or from each other.

11. A sheet feeding mechanism comprising a support for a stack of sheets to be separated, a sheet separating device having a plurality of linearly disposed teeth, means for moving said device toward the side of said stack and angularly upwardly along the face of said stack to separate the edge portion of one or more sheets from the stack or from each other, and means to remove said top sheet when separated by said device.
